UNITED STATES PATENT OFFICE

156,577

COMBINED CIGARETTE BOX, ASH TRAY,
AND MATCH HOLDER

Charles H. Strange, White Plains, N. Y.

Application March 4, 1948, Serial No. 144,907

Term of patent 14 years

(Cl. D85—2)

To all whom it may concern:

Be it known that I, Charles H. Strange, a citizen of the United States, residing at 38 Normandy Road, White Plains, county of Westchester, and State of New York, have invented a new, original, and ornamental Design for a Combined Cigarette Box, Ash Tray and Match Holder, of which the following is a specification, reference being had to the accompanying drawing forming part thereof, and in which:

Figure 1 is a side view of a combined cigarette box, ash tray, and match holder, in closed position, showing my new design.

I claim:

The ornamental design for a combined cigarette box, ash tray, and match holder, as shown.

CHARLES H. STRANGE.
